CLAIM

The ornamental design for a reel seat and foregrip with exposed blank for fishing rod handle, as shown and described.

DESCRIPTION

FIG. 1 is a perspective view of a reel seat and foregrip with exposed blank for fishing rod handle showing my new design;

FIG. 2 is a front view thereof;

FIG. 3 is a rear view thereof;

FIG. 4 is a side elevational view of one side thereof;

FIG. 5 is a side elevational view of the other side thereof;

FIG. 6 is a top view thereof; and,

FIG. 7 is a bottom view thereof.

The broken line showing of a fishing rod handgrip portion, locking nut, and blank is for illustrative purposes only and forms no part of the claimed design;
